UNITED STATES PATENT OFFICE.

ALANSON P. BRUSH, OF DETROIT, MICHIGAN.

CARBURETER.

1,130,474.

Specification of Letters Patent.

Patented Mar. 2, 1915.

Application filed June 2, 1913. Serial No. 771,195.

To all whom it may concern:

Be it known that I, ALANSON P. BRUSH, a citizen of the United States, residing at Detroit, in the county of Wayne and State 5 of Michigan, have invented a certain new and useful Improvement in Carbureters, of which the following is a full, clear, and exact description.

The invention relates to carbureters adapted for use in connection with internal combustion engines which employ gasoline or other liquid hydro-carbon as the source of fuel supply.

The object is to produce a carbureter 15 which is so organized that it will furnish, under all the varying conditions of practical service, an adequate and substantially uniform supply of mixed air and hydro-carbon vapor.

20 The invention is what is generally classified as a multiple jet carbureter. But the most important characteristic of this invention is the location of plural fuel delivery orifices in different relations to that air inlet 25 passage or zone of suction which is created and enlarged by the movement of an air valve from its seat as the result of the suction created by the suction strokes of the engine,—the arrangement of said fuel discharge orifices being such that they will progressively come to be within the zone of suction as said zone is widened by the opening of the air valve.

25 The invention also includes other features 35 of more or less importance which contribute their part to the efficiency of the device; and all of these are definitely set forth in the appended claims; and the invention embodied in the best known form is hereinafter described and shown in the drawing, in which

Figure 1 is a central vertical section of the carbureter. Fig. 2 is another central vertical section at right angles to that shown in Fig. 1. Fig. 3 is a sectional plan in the plane indicated by line 3—3 on Fig. 1; and Fig. 4 is a plan view of the carbureter when the upper casing member has been removed therefrom.

30 The carbureter casing includes three principal members, to wit, the lower member A which is a so-called float chamber for containing the liquid hydro-carbon; the intermediate member B which supports the fuel nozzles and the air valve; and the upper member C which contains the mixing chamber in which is the air throttling valve F.

This member C is to be connected with the intake manifold of the engine.

The intermediate member B has an axially disposed vertical hole through it within the 60 downwardly extended cylindrical flange b, and the upwardly extended cylindrical flange b¹ of larger diameter. A tubular bolt E which passes through a hole in the bottom of the member A screws into the lower end 65 of the tube b, and thereby members A and B are secured together. The member B has likewise a plurality,—in the present instance four,—outwardly and upwardly extended arms b²; and it is to the upper end of 70 these arms that the upper member C is secured by screws or other suitable means. Surrounding this mixing chamber and within the casing member C is the annular jacketing space c, across which is the vertical partition c¹. A pipe K, which is to be connected with exhaust pipe of the engine and which is not intended to contain any valve or other means for restricting its size, is connected with the inlet to this jacketing 75 space so that the hot exhaust gases may freely flow into said jacketing space. Once in, they are obliged to flow around the mixing chamber, and must escape through a plurality of small openings c². The shaft f 80 to which the valve F is fixed extends up through the walls of the member C, and it has an operating lever f¹ secured to one end. To its other end a shutter valve f² is secured. This shutter valve is so shaped and connect- 85

ed with the shaft that when the throttle valve is opened this shutter will cover all, or nearly all of the outlet orifices c². When, however, the throttle valve is being moved to the closed position, this shutter will be 90 moved toward a position such that all of these orifices are uncovered. The volume of the hot exhaust gases which flow through the jacketing space referred to will therefore be greatest when the throttle valve is 95 closed or nearly closed, and will be gradually reduced as the throttle valve is opened; because, although there is no impediment to the entrance of the exhaust gases through pipe K, the escape of said exhaust gases 100 from the jacketing space is impeded to a greater or less extent by said shutter valve.

The lower end of the annular mixing chamber is outwardly tapered, thereby forming a conical seat c³ for the air valve D. 110 This valve is so constructed and combined with other parts that it will be drawn from

its seat a distance dependable upon the reduction of pressure within the mixing chamber produced by the suction strokes of the engine. In the specific construction shown, 5 this valve is in the form of an inverted cup whose lower end is of greater diameter than the upper end which engages the valve seat. This lower end fits slidingly over the tube b^1 . There is a hole formed centrally 10 through the upper end of this valve, and in this hole a downwardly extended tube d is fixed, which tube slidingly fits over the upper end of the rod H . This rod is tightly fitted in the tubular hole in the bolt E 15 through which it passes, and in the lower end of which it is screwed for the purpose of adjustment. In the upper part of this rod there is an air duct h which extends from its upper end downward and then laterally so as to communicate with the space 20 within the flange b , which space is in free communication with the space below valve D . A spring I embraces the rod H and is compressed between a shoulder h^1 on said 25 rod and a shoulder d^2 on tube d . This spring, therefore, acts to hold the air valve against its seat. When, through the effects of the suction strokes of the engine, the pressure within the mixing chamber is sufficiently 30 reduced, the pressure below the valve D will be similarly reduced, wherefore the atmospheric pressure upon the outwardly extended external flange d^3 of the air valve will cause said air valve to move downward 35 away from its seat. The distance which it so moves will be proportionate to the degree of vacuum within the mixing chamber. The movement of the valve from its seat produces an annular passage through which 40 air may be freely drawn. The air will flow through this passage with great rapidity, and will produce a suction effect which will draw fuel from any fuel nozzle whose outlet is within the zone of the suction influence. 45 These parts of the annular space which is widened and narrowed by the movement of the air valve from its seat within which the suction influence is sufficient to draw fuel from a properly placed nozzle constitute 50 what will, for convenience, be herein referred to as the zone of suction. This zone of suction includes the annular opening between the valve seat and the part of the valve which engages therewith, and it includes also some area adjacent thereto. 55

A plurality of nozzles are employed; and they are differently placed with respect to the enlargeable zone of suction. Each nozzle is crewed at its outer end into the associated arm b^2 so as to freely communicate with a fuel duct therein b^3 . Each duct is connected with a fuel pipe 5 which extends down into the fuel within the float chamber A . The starting or idling nozzle N is located in a groove c^4 in the valve seat c^3 , and

the discharge orifice of said nozzle is just above the top of the air valve. When the suction effect of the engine is not sufficient to open the air valve all of the air drawn in on the suction strokes will flow through this groove around the nozzle; and, in flowing, will draw from the nozzle sufficient fuel to mix with said air to form the required explosive mixture. It will be noted that this nozzle, and, in fact, all of the nozzles are 70 adjustable in position. That is to say, they may be screwed backward or forward in the supporting arm b^2 so as to change the position of the discharge orifices. The nozzle N is also provided with an adjustable needle valve by means of which to vary the size of the discharge orifice. With one or the other or both of these adjustments it will be possible to so adjust the size and position of the nozzle that the proper proportion of 75 fuel will be drawn from the nozzle to mix with the air flowing into the mixing chamber adjacent to the nozzle. The other nozzles have their discharge orifices at different distances away from the air valve. The 80 nozzles are all preferably inclined at the same angle as the valve slot c^3 and lie in contact with said valve slot. The nozzle N^1 has its discharge orifice so placed that when the air valve has opened, let us say an eighth 85 of an inch, the effective zone of suction created by the in-rushing air through the annular air passage will include nozzle N^1 , but will not include the two nozzles N^2 , N^3 . When, by the further opening of the air valve, the 90 effective zone of suction is still further widened, it will next come to include the nozzle N^2 , and when the valve is still further opened, and the effective zone of suction still more widened by such opening, 95 the fourth nozzle N^3 will be included within the effective zone of suction. Fuel will be drawn from as many of the nozzles as are brought into the effective zone of suction by the widening of such zone, due to the opening 100 of the air valve. 105

Having described my invention, I claim:

1. In a carbureter, the combination of a mixing chamber, a suction operated air valve controlling the admission of air thereto, and a plurality of fuel discharge orifices which are differently arranged with respect to the air valve and to the zone of suction which is created and widened by the opening of the air valve, whereby the said nozzles will be progressively included within said widening zone of suction, and means for independently adjusting the nozzles to change the position of their discharge orifices with respect to said zone of suction. 115

2. In a carbureter, the combination of a mixing chamber, containing a throttle valve and having at its lower end a tapered valve seat, a vertically movable hollow air valve adapted to engage at its upper end with 120

said seat, which air valve is of greater external diameter at its lower end than at the upper end thereof which engages with said seat, and there being air ducts which establish communication between the mixing chamber and the under side of said air valve, a guide flange which projects into the lower end of said air valve and forms therewith a chamber which is closed except 10 for the air duct referred to, a plurality of inclined fuel discharge nozzles arranged around the said air valve with the discharge orifices of said nozzles at different distances from that part of the valve seat with which 15 the valve engages.

3. In a carbureter, the combination of a mixing chamber, containing a throttle valve and having at its lower end a tapered valve seat, a vertically movable hollow air valve 20 adapted to engage at its upper end with said seat, which air valve is of greater external

diameter at its lower end than at the part which engages with said seat, and there being air ducts which establish communication between the mixing chamber and the 25 under side of said air valve, a guide flange which projects into the lower end of said air valve and forms therewith a chamber which is closed except for the air duct referred to, a plurality of inclined fuel discharge orifices of said nozzles at different distances from that part of the valve seat with which the valve engages, said valve seat having a groove which communicates with the mixing chamber, and a fuel nozzle located with- 30 35 in said groove.

In testimony whereof, I hereunto affix my signature in the presence of two witnesses.
